(57) **CLAIM**

The ornamental design for a radiographic shield, as shown and described.

DESCRIPTION

FIG. 1 is a perspective view of a radiographic shield embodying the invention in a first position;

FIG. 2 is a top view of the radiographic shield of FIG. 1;

FIG. 3 is a left side view of the radiographic shield of FIG. 1; and,

FIG. 4 is a perspective view of the radiographic shield of FIG. 1 in a second position.

The bottom and rear views of the radiographic shield are not shown in the drawing or described in the specification. It is understood that the appearance of any part of the article not shown in the drawing or described in the specification forms no part of the claimed design.

1 Claim, 3 Drawing Sheets

FIG. 3

FIG. 2

FIG. 4
